UNITED STATES PATENT OFFICE.

MICHAEL McANENY, OF ST. LOUIS, MISSOURI, ASSIGNOR TO HANDILITE MANUFACTURING COMPANY, A CORPORATION OF MISSOURI.

CIGAR-LIGHTER.

1,103,307.

Specification of Letters Patent. Patented July 14, 1914.

Application filed October 11, 1913. Serial No. 794,641.

To all whom it may concern:

Be it known that I, MICHAEL McANENY, a citizen of the United States, and resident of St. Louis, State of Missouri, have invented 5 a certain new and useful Improvement in Cigar-Lighters, and do hereby declare that the following is a full, clear, and exact description thereof.

The object of my invention is to provide 10 a self-contained flame-producing device especially adapted for cigar lighting of the type having a spark-producing mechanism in the form of a rotary abrading disk and a body of pyrophorous alloy, or other spark-producing medium, which will be of simple 15 and compact construction so that it will take up but little room and will be certain in its action, and to this end my invention consists in the lighter constructed substantially 20 as hereinafter specified and claimed.

In the accompanying drawings—Figure 1 is a perspective view of a cigar lighter embodying my invention; Fig. 2 a side elevation thereof; Fig. 3 a view partly in elevation and partly in vertical section; Fig. 4 a detail view in perspective of a portion of the mechanism for producing the spark.

In the form in which my invention is shown as embodied, the body 10 is preferably of cylindrical form and hollow to form 30 a receptacle for some readily inflammable fluid, such as alcohol, or gasoline; and which at its top has a wick tube 11 through which passes the wick 12 that leads from 35 within the box 10. The box 10 may be mounted upon any desired form or support, such for example, as a circular tray or disk which renders it convenient for use on the tables of cafes, or it may be attached to a 40 small bracket in a stationary position upon cigar stand counters. Contiguous to the wick tube is an igniting-spark producing device in the form of an abrading wheel or disk and a plug of pyrophorous alloy that 45 bears against the edge of the disk so that by turning the latter sparks will be produced and projected over the exposed top of the wick. The disk or wheel 13 is mounted loose on the upper end of a vertical shaft

14 which is journaled in a bracket 15 upon 50 one side of the box 10, and upon its underside said disk has ratchet teeth 16 adapted to be engaged by ratchet teeth 17 on a collar 18 slidably and rotatably fastened to the shaft 14 by a pin 19 which passes diametrically through the shaft and at its ends engages vertical slots 20 in the collar. A spring 21 is placed around the shaft between the underside of the collar and the top of the bracket that yieldingly holds the ratchet 60 teeth in engagement and permits the teeth to slip past each other when the shaft turns in one direction, so as not to revolve the disk, while compelling their engagement when the shaft turns in the opposite direction and causing the disk to turn. Thus, 65 sparks are produced only when the shaft turns in one direction which is the one required to throw sparks over the wick, and there is no needless production of sparks and 70 waste of the alloy.

On the shaft 14, just below the top of the bracket 15 is fixed a collar 22 from which projects a radial arm 23 that is slotted or bifurcated to form two oppositely positioned 75 fingers 24 between which fingers is situated the upper end of an elastic or spring blade or strip 25 which is attached to and projects from an operating lever 26 which is pivoted upon a horizontal shaft 27 supported between lugs 28 projecting from the side of the box or body 10. It will be seen that if the shaft 14 is restrained from rotation and the operating lever is pressed inward toward the lamp body the elastic blade or 80 spring plate will be bowed and placed under tension between the lever pivot and the shaft fingers between which the upper end of said blade lies and upon the release of the shaft 14 said spring blade will react and quickly 85 and forcibly by its action upon the finger carrying arm 23 will rotate the shaft 14 in the direction to cause the turning of the abrading disk for the production of a spark. For preventing the rotation of the shaft 14, 90 until the desired tension is produced by the bowing or flexing of the spring and then automatically to release the shaft, the latter 95

at its lower end has a radial pin 29 in the path of which is yieldingly held an escapement like tooth 30 on a lever 31 pivoted to the side of the lamp body and lying along-
5 side of the operating lever 26, but situated sufficiently nearer to the side of the lamp body to prevent its being engaged by the hand of the user when applied to the operating lever 26 until the operating lever has
10 been pressed toward the lamp body sufficiently far to produce the desired tension upon the spring blade, whereupon said locking tooth carrying lever 31 will be moved inward toward the lamp body to carry the
15 tooth out of the path of the radial pin 29 on the shaft and thereby free the shaft for the action of the spring blade. The tooth-carrying lever is normally and yieldingly held so that the tooth is in position to engage
20 the radial pin on the shaft by some suitable spring device, such for example, as that shown in the drawings which consists of a coil spring 32 in a housing on the side of the lever which bears at one end against a
25 pin 33 that at its other end bears against the outer side of the lamp body. The operating lever and the spring blade carried thereby are moved in the reverse direction to that for placing the spring blade under tension by
30 means of a spring 34 secured at one end between the lugs to which the lever is pivoted and at its other and outer end bearing against the inner side of the lever. It will be seen that the reversal of the lever serves
35 to restore the shaft 14 to the position from which it is turned by the reaction of the spring blade and the position where it is latched by the engagement of the tooth 30 of the latch lever 31 with the radial pin 29 on
40 the shaft. The spring blade is also the instrumentality for operating the snuffer to extinguish the light. The snuffer consists of a hood 35 pivoted to one side of the wick tube, and having a curved slotted crank arm
45 36 into the slot of which projects a pin or stud 37 on the spring blade so that when the latter moves to cause tension to be placed upon it in order to produce the spark, the hood will be swung from over the wick to
50 expose the latter to the spark while when the spring blade is moved in the reverse direction by the action of the spring 32 when the operating lever 26 is released the hood is automatically swung over the wick and
55 snuffs out the light. It will be seen that so long as the operating lever is restrained by the grasp of the hand the light will continue to burn because the snuffing hood is maintained in a position at one side of the light
60 It will be seen that although I have two levers, one of which places the spring under tension and the other acts to release the abrading disk operating shaft when the desired tension of the spring is secured, that

the relative position of the two levers is such 65 that in grasping the lighter to produce the light both levers are certain to be actuated.

The plug of pyrophorous or other spark-producing medium, is mounted in a horizontal tube 39 carried by an arm fixed to the 70 wick tube with one end contiguous to the disk periphery and its other end closed by a screw cap 40 between which and the outer end of the plug is a coiled spring 41 by which a gentle pressure is maintained on the 75 plug to keep it in proper engagement with the abrading disk. The cap 40 provides adjustment to compensate for the natural wear of the plug.

With my lighter the movement of the 80 snuffer is so timed that it does not uncover the wick until the spark is to be produced so that any gas or vapor accumulating under the snuffer is retained for the reception of the spark; the abrading wheel is always exposed to the air so that it cannot become damp as is possible where such wheel is covered or housed; and the vertical position of the wheel shaft or its parallelism with the wick tube is very advantageous because the 90 wick and wheel can be placed very close together and thus make it certain that the spark will be thrown to the wick.

It will be understood that departure may be made from the form and construction 95 of the members of my lighter without departing from the scope of my invention, and I, therefore, do not restrict myself only to the lighter having the form and construction of parts shown in the drawings. 100

Having thus described my invention what I claim is—

1. A lighter comprising a spark-producing mechanism consisting of relatively stationary and movable members and a rotatable shaft for moving the movable member, a spring connected with the movable member, an operating handle for placing the spring under tension, and releasable means having an operating handle acting to prevent movement of the movable member until the spring has been placed under the desired tension. 105

2. A lighter comprising spark-producing mechanism including a rotatable disk, an operating shaft for the disk, a spring blade connected with the shaft, a lever carrying said blade, and a releasable latch device to prevent the shaft from turning. 115

3. A lighter comprising spark-producing mechanism including a disk, an operating shaft for the disk having a radial arm, a spring blade engaging said arm to rotate the shaft in either direction, a lever carrying said blade, and a releasable latch device to prevent rotation of the shaft. 120

4. A lighter comprising spark-producing mechanism including a disk, an operating

shaft for the disk having a radial arm, a spring blade engaging said arm to rotate the shaft in either direction, a lever carrying said blade, a releasable latch device to prevent rotation of the shaft, a snuffer, and connections between the snuffer and the spring blade.

In testimony that I claim the foregoing I have hereunto set my hand.

MICHAEL McANENY.
